ATTORNEY

UNITED STATES PATENT OFFICE.

ROBERT G. CULP, OF CONEMAUGH, PENNSYLVANIA.

MAIL-BAG-RECEIVING APPARATUS.

1,219,441.

Specification of Letters Patent. Patented Mar. 20, 1917.

Application filed June 30, 1916. Serial No. 106,904.

To all whom it may concern:

Be it known that I, ROBERT G. CULP, a citizen of the United States, residing at Cone-
maugh, in the county of Cambria and State
of Pennsylvania, have invented certain new
and useful Improvements in Mail-Bag-Re-
ceiving Apparatus, of which the following
is a specification.

This invention relates to certain new and
useful improvements in mail bag receiving
apparatus.

The primary object of this invention re-
sides in the provision of a mail bag receiving
apparatus which will be of improved and
simplified construction and highly efficient
in use.

Another object of the invention resides in
the provision of a mail bag receiving appa-
ratus of this character which may be espe-
cially adapted for use in connection with a
mail bag delivering crane or mechanism of
the type disclosed in my application Serial
No. 83357.

A further object of the invention resides
in the provision of a mail bag receiving appa-
ratus which may be positioned between
tracks and will include supporting arms hav-
ing inclined upper faces and spring latch
members for engagement with said inclined
upper edges to lock the mail bag upon the
same.

With these general objects in view and
others that will appear as the nature of the
invention is better understood, the same con-
sists in the novel combination and arrange-
ment of parts hereinafter more fully de-
scribed, illustrated in the accompanying
drawing and pointed out in the appended
claim.

40 In the accompanying drawing, I have
shown a perspective view of the complete
device in use.

Referring more particularly to the draw-
ing, 1 designates a base upon which the
45 standard 2 is mounted, the lower portion 3
of the standard being enlarged and having
oppositely directed arms 4 projecting hori-
zontally from the same, the ends 5 of said
arms 4 being extended upwardly. The
50 upper and lower portions of the standards 2
are connected by suitable brace rods 6 with
the arms 4. Additional brace rods 7 also
connect the upwardly extended ends 5 of the
arms 4 with the main portion of the latter.

55 Mounted upon the upwardly extended
ends 5 of the arms 4 are the oppositely ex-

tended mail bag receiving arms 8 which are
provided with inclined upper faces 9, one
arm 8 being provided for each arm 4.
Spring latch plates 10 are secured by one
end to the upper extremities of the arms 4
and extend over the arms 8, the free ends 11
of said latch plates 10 being curved out-
wardly. Each latch plate 10 carries a tri-
angular latch member 12, one point of which
rests upon the inclined upper edge 9 of the
arm 8 over which the latch plate 10 is ex-
tended. It will therefore be seen that a mail
bag carrying hook 13 may be readily re-
moved from its support carried by the pass-
ing car, the hook 13 riding up the inclined
edge 9 of the arm 8 and forcing its way
along the latch member 12, said latch mem-
ber 12 automatically returning to normal
position to prevent the hook 13 from sliding
back off of the arm 8. While any suitable
form of hook 13 may be employed for sup-
porting the mail bag 14, I prefer to employ
the form of hook shown in the drawing and
provided with a flat lower side 15 with the
shank 16 of the hook depending from the
same for removable engagement with the
hook 17 or other member carried by the mail
bag 14. Any suitable crane or supporting
means 18 will also be employed and mounted
in any preferred manner upon the car.
Therefore, the crane will not be specifically
described. A complete description of the
form of crane shown may be found in my
copending application Ser. No. 83,357, pre-
viously referred to.

The standard 2 is provided with oppo-
sitely directed mail bag supporting arms 19
which are parallel with the arm 8 and have
inclined upper faces 20 with which are con-
nected the lower points of the triangular
latch members 21 carried by the double
spring latch plate 22. This spring latch
plate is secured centrally to the upper end
of the standard 2 and projects over both of
the arms 19, the free ends 23 of said spring
latch plate 22 being curved upwardly. It
will therefore be seen that the mail bags
may be properly supported upon the arm 8
to be removed by proper mechanism carried
by the passing car, while other mail bags are
delivered to the arms 19.

While the form of the invention herein
shown and described is what is believed to be
the preferred embodiment thereof, it is
nevertheless to be understood that minor
changes may be made therein without de-

parting from the spirit and scope of the invention as claimed.

What I claim as new is:—

In a mail bag deliverer and receiver the combination with a support of a plate mounted on the support having its upper edge beveled from the center thereof in divergent directions to the extremities of the plate, a resilient latch comprising a resilient longitudinal strip secured to the plate at its

highest point and having its ends curved upwardly, and keeper legs carried by the resilient strip and bearing against the inclined edges of the first named plate.

In testimony whereof I affix my signature 15 in presence of two witnesses.

ROBERT G. CULP.

Witnesses:

SAL JOFFE,

ROSE M. MÜNZER.
